UNITED STATES PATENT OFFICE

1,967,517

METHOD AND APPARATUS FOR HANDLING
PIPE IN WELLSWalter A. Rogers, Houston, Tex., assignor of
sixty-five per cent to Lester B. Clark, Houston,
Tex.

Application June 26, 1933, Serial No. 677,572

11 Claims. (Cl. 255—1)

My invention relates to apparatus used around the drilling rig employed in drilling deep wells for oil, gas, sulphur and the like.

In drilling operations it is the usual method, particularly in the rotary type of drilling apparatus, to attach the drill at the lower end of the hollow drill stem and to employ a kelly joint or drive stem at the upper end to communicate rotation to the drill stem. When the drill has advanced sufficiently to necessitate the insertion of another section of drill stem, the driller then detaches the kelly joint from the upper end of the length of drill stem in the well and swings the kelly, together with the swivel and its connections, over to one side of the derrick and drops the kelly into a specially drilled "rat hole" where the kelly is left while the draw works are employed in lifting up another section of pipe and attaching it to the section or sections already in the well. After this new section of pipe has been attached, the drill pipe is lowered so that the upper end of the newly attached section is just above the rotary; the traveling block and elevator is then lowered and secured to the kelly joint, which is again raised up in the derrick and the lower end thereof is again attached to the upper tool joint box on the new section of pipe. This method is one in general use and is as economical in the consumption of time as any other method now in use.

It is an object of my invention to provide a method and apparatus whereby this process of inserting a new section of pipe may be greatly facilitated so as to consume less time and to increase the safety factor in the operation.

It is another object of the invention to provide a means for temporarily connecting to the kelly joint a new section of pipe which may be swung into position and attached to the sections of drill stem already in the well without the necessity of detaching the kelly joint from the traveling block.

A mechanical feature connected with my invention includes the use of a special construction of double-ended elevator whereby a flexible connection can be quickly made between the kelly joint and the new section of pipe which is to be handled.

I also provide a means for temporarily suspending a new section of pipe in the derrick ready for use as soon as it is required. These and other features of construction making up my invention will be more particularly set out in connection with the drawings wherein:

Fig. 1 is a side view of the lower portion of a

well derrick equipped to carry out my invention.

Fig. 2 is a similar view showing the parts in different position and illustrating the manner in which the new section of pipe is handled.

Fig. 3 is a front elevation of my double-ended elevator employed in connection with the invention.

Fig. 4 is a side elevation of one portion of the elevator showing the use of the eyelet whereby the elevator can be supported out of the way when not in use.

Fig. 5 is a top plan view of the elevator shown in Fig. 3.

In Figs. 1 and 2 the usual apparatus employed in handling the pipe is shown somewhat diagrammatically, the draw works themselves being omitted. Referring particularly to Fig. 1, the usual derrick is shown at 1, with the upper portion including the crown block broken away, it being understood that no variation from the usual type of equipment in the derrick for handling the pipe is contemplated.

The drill stem which is attached to the drill and rotated in the drilling operation is understood as being of the usual type and connected at its upper end to a special drive stem or kelly joint 2. This kelly joint may be of any desired construction. It is ordinarily polygonal in shape and fits slidably through a bushing 3 in the rotary table 4 employed in the rotation of the drill stem. The rotary table is understood as being operated through the usual mechanism employed in drilling. The upper end of the kelly joint 2 is connected to a swivel 5, which is suspended by means of a bail 6 to the hook 7 on the traveling block 8. The swivel includes a stationary goose-neck connection 9, which has a swivel connection with the upper end of the kelly joint 2. The goose-neck 9 is connected through the usual reinforced mud hose 10 with the mud pump not shown, this being the usual construction.

It is to be understood that as the hole is deepened the kelly joint 2 with the drill sections below it are gradually lowered into the well until it becomes necessary to attach another section of drill stem.

Instead of releasing the kelly joint from the traveling block as is usually done in handling the new section of pipe, I contemplate raising the kelly joint in the usual manner until the upper end 11 of the drill stem is exposed above the rotary table. I then support the drill stem by the usual slips 12 in the table and detach the kelly joint therefrom. I then couple to the end of the new section of drill stem 13 a specially con-

structed double-ended elevator shown at A in the drawing. The lower end of the kelly joint is then swung over in the derrick and the upper end of the elevator is coupled to the lower end 5 of the kelly joint, this arrangement permitting swinging movement of the new section relative to the kelly joint as they are coupled together in spaced relation. The new section of pipe is then 10 swung up into position, as shown in Fig. 2, by raising the kelly, elevators and new section of pipe and its lower end is then lowered into connection with the upper box 11 of the drill stem and the usual connection is made.

The next step is to lower this new section of 15 pipe and the drill stem so that the upper end is near the rotary table. As soon as this new section of pipe is properly supported on the slips, then the kelly joint is lowered and threaded onto the new section or the lower elevator of the apparatus can be detached and the kelly joint lowered and connected to the upper end of the 20 new section of pipe 13. The upper elevator can then be detached from the kelly joint and the entire apparatus placed in its position on the 25 derrick floor, as shown in Fig. 2, ready for attachment to another section of the pipe to be used in the next operation.

As shown in Figs. 1 and 2, I contemplate temporarily holding the elevator A in position at 30 one side of the derrick platform by connecting the same to a cable 14, which is suspended around a pulley 15 in the derrick and its free end swung down along the side of the derrick and has a weight 16 secured thereto. The weight 16 being 35 approximately the same as the weight of the elevator, it will be easy at all times to raise and lower the elevator in use without other special equipment.

The structure of the elevator will now be described. Referring particularly to Figs. 3, 4 and 40 5, it will be noted that the elevator A is composed of two elevators flexibly connected together. The upper elevator 17 is approximately the same as the lower elevator 18, except that the bail connections on the two elevator blocks 45 are reversed in position. Each of the blocks comprises two approximately semi-circular sections 19 and 20, which are hinged together at one side by hinge pins 21 and are adapted to latch together on the opposite side by a latch including a T-shaped latch member 22, which is pivoted at one end upon a pin 23 secured through two outwardly extending lugs 24 on the section 20. The head 25 is adapted to latch over the ends of two 50 spaced lugs 26 on the section 19 of the elevator. The latch is normally held in latching position by means of a spring 27 on the pin 23. Each of the sections 19 and 20 may have thereon outwardly extending handles 28. In this portion 55 of the construction the elevator blocks are of ordinary commercial construction.

The upper elevator member has on its side 60 thereof outwardly extending supports 29 and lower arms 30. A bolt 31 may be extended through the outer ends of two projecting arms 65 and be secured therein by means of nuts 32. The lower arm 30 is substantially stronger than the upper arm and is recessed slightly at 33 to receive the bail 34, and it will be understood that when 70 the upper elevator is secured around the lower end of the kelly joint indicated at 35, in Fig. 3, the lower elevator member will be suspended flexibly thereto by means of the bail members 34.

The lower ends of the bails are connected to the 75 arms 30' on the lower elevator and it will be noted

that the lower elevator has the arms 30' and 29' reversed in position upon the elevator so that the bails 34 are connected with the arms 30' so as to suspend the lower elevator from the upper one.

At one side of the upper elevator I connect an eyelet 36 whereby the hook on the suspending cable 14 may be temporarily attached thereto when the elevator is not in use. This eyelet comprises an approximately U-shaped clevis, the ends of which are secured one beneath the head of the hinge pin 21 and the other between the two sections of the elevator at the hinge, as shown particularly in Fig. 4.

It will be obvious that with the use of my improved form of elevator I am enabled to handle the connection of new sections of pipe in the drill stem with less loss of time and with greater convenience to the operator than can be done by the old method.

It will not be necessary to use a "rat hole" into which the kelly joint may be supported while a new section of pipe is being handled by elevators in the usual method. All that is necessary is to detach the kelly and engage the elevator with the lower end of the kelly and the upper end of the new section and swing the said new section into position and connect it with the drill stem. The elevator may then be swung out of position ready for attachment to a new section of pipe and the kelly may be connected and the drilling proceed without delay. This avoids a loss of time which is serious in the expense of drilling a well and is much more convenient and desirable from the standpoint of the operator. The advantages will be understood by those skilled in the art.

What is claimed as new is:

1. An elevator for wells comprising upper and lower tubular collars, each longitudinally divided into two sections, a hinge at one side of each collar, a latch thereon opposite said hinge, the latches on said collars being longitudinally aligned to open on the same side thereof, bail supporting arms on said upper collar, arms on said lower collar engaged by said bail and means to retain bails on said arms.

2. A pair of elevator collars each adapted to latch about a different pipe, bail engaging arms adjacent the lower end of one of said collars, similar arms adjacent the upper end of the other of said collars, and bails engaging said arms and flexibly connecting said collars whereby the pipe engaged by one collar may be used to lift the elevator and pipe engaged by the other collar.

3. Upper and lower elevator collars each adapted to latch about a different pipe, laterally projecting arms on each collar and bails engaging said arms to flexibly connect said collars whereby the ends of the two different pipes may be supported in spaced apart relation or coupled together.

4. In a well drilling apparatus including a sectional drill stem, a kelly joint thereon, and a hoisting cable connected therewith for raising and lowering said kelly joint and drill stem, the method of attaching additional sections of drill stem including detaching the kelly joint from the drill stem, swinging said kelly joint to a point adjacent said new section, connecting said kelly joint flexibly with said new section of drill stem, raising said kelly joint and said new section to a position above said drill stem, attaching said new section to said drill stem, disconnecting said flexible connection and screwing said kelly joint to said new section.

5. In the operation of rotary well drilling, the method of adding new sections of drill stem in

- the main string of drill stem, comprising unscrewing the kelly joint from the drill stem, connecting the lower end of said kelly joint flexibly with the upper end of the new section, raising the kelly joint and said new section to position above said drill stem, connecting said new section with said drill stem, releasing said flexible connection and attaching said kelly joint to said new section. 5 80
- 10 6. In the operation of rotary well drilling the method of adding new sections of drill stem in the main drill stem string comprising detaching the kelly joint, connecting the upper end of the new drill stem section to said kelly joint, raising said new section to position above said drill stem and attaching said new section to the upper end of said drill stem. 85
- 15 7. An elevator for handling two uncoupled pipe sections comprising upper and lower pipe engaging collars each longitudinally divided into sections, a hinge at one side of each collar, a latch thereon opposite said hinge whereby each collar may be engaged about a pipe, bail supporting arms on said upper collar, arms on said lower collar, bails engaging both sets of said arms whereby the two collars are spaced apart so that the pipe end engaged by each collar may be spaced from the other, and means to retain said bails on said arms. 90
- 20 8. A device of the character described, upper and lower pipe-receiving elevator collars adapted to latch about the pipe received, and means flexibly connecting said collars together whereby the pipe engaged by the upper collar may be disposed 95
- 25 at an angle with respect to the pipe engaged by the lower collar. 100
- 30 11. In the art of drilling wells by the rotary method by adding sections of drill pipe to the drill stem as the drilling progresses and wherein the drill stem is rotated by a kelly joint, the steps of disconnecting the kelly joint from the drill stem when a new section is to be added, coupling the lower end of the kelly joint to the new section so that the new section may have 105 swinging movement relative to the kelly joint, raising the kelly joint and new section while coupled so that the new section will swing into line with the drill stem, and then successively connecting the new section and the kelly joint to rotate the drill stem. 110
